UNITED STATES PATENT OFFICE.

AXEL A. STROM, OF AUSTIN, ILLINOIS, ASSIGNOR, BY MESNE ASSIGNMENTS,
TO THE WALMSLEY & COMPANY, OF CHICAGO, ILLINOIS.

APPARATUS FOR GENERATING ACETYLENE GAS.

SPECIFICATION forming part of Letters Patent No. 608,804, dated August 9, 1898.

Application filed June 14, 1897. Serial No. 640,734. (No model.)

To all whom it may concern:

Be it known that I, AXEL A. STROM, a citizen of the United States, residing at Austin, in the county of Cook and State of Illinois, have invented a new and useful Improvement 5 in Apparatus for Generating Acetylene Gas, of which the following is a specification.

My invention relates to an improvement in the class of apparatus for generating gas from 10 calcium carbid and water (or from any other solid and liquid substances which generate gas by bringing them together) in which provision is made for automatically checking generation of the gas whenever a sufficient 15 or predetermined supply has been produced and for automatically resuming the generation whenever the supply becomes insufficient.

The primary general object of my improvement 20 is to provide a construction of the gas-generating apparatus whereby it shall be adapted to be placed in position for use, as in a household, upon merely coupling it as a gas-meter is coupled with the pipe system 25 in the house, so that the installation may be performed with extreme facility and without the aid of skilled labor.

Another object of my invention is to provide the generator proper as an extraneous 30 part of the apparatus wholly independent for its support of any other part of the apparatus and adapted to be so readily connected with the gasometer and disconnected therefrom that charging it with carbid is rendered a 35 matter of ease and emptying it of the sediment is rendered as convenient as emptying the ashes from a bucket.

Further objects are to improve the valve mechanism for controlling automatically the 40 supply of water to the carbid-holder by the action of the gas-holder and also to improve the construction of the apparatus generally in matters of detail and combinations of parts.

Referring to the accompanying drawings, 45 Figure 1 is a view in sectional elevation, partly diagrammatic in its nature, taken at the line 1 on Fig. 2 and viewed in the direction of the arrow and showing the two differentially-weighted gas-holders which I prefer

to employ, with their means of intercommunication and the means for connecting them with the extraneous gas-generating carbid-holder; Fig. 2, a section taken at the line 2 on Fig. 1 and viewed in the direction of the arrow; Fig. 3, a section taken at the line 3 on Fig. 3 and viewed in the direction of the arrow; Fig. 4, a section taken at the line 4 on Fig. 3 and viewed in the direction of the arrow; Fig. 5, a plan view, partly broken, showing a modified construction of the generator-cover and its pipe connections; and Fig. 6, an enlarged view, in sectional elevation, of the valve mechanism provided in the gas-holder for controlling the supply of water therefrom to the carbid-holder. 50 55 60 65

A is the carbid-holder or generator proper, the preferred construction of which is shown in detail in Figs. 3 and 4. It comprises a can or box A', preferably of the circular shape illustrated, formed of sheet metal and having the conical top r, containing the opening r', about which is fastened the collar r², of heavier metal, containing the annular seat r³ for the lid A², between which and its seat suitable packing r⁴ should be provided. The lid A² has a central opening p, surrounded by a collar p', and between the collar and the opening is a seat p², having the offset p³, respectively for the flange q and extension q' of a hollow head A³, suitable packing p⁴ being provided between the flange and its seat. The head A³ contains the chambers o and o', the former being closed at its base, from which there depends over the center of the can A a nozzle n, pointed toward its lower end, in opposite sides of which are provided the minute water-outlet openings n' n'. A water-inlet pipe m leads into the chamber o of the head A³, and a gas-outlet pipe m' leads from the chamber o', and the pipes m and m' contain 80 85 90 95 shut-off valves (indicated at s and s' in Fig. 2) of ordinary or any suitable construction on a common stem s², extending between the pipes and carrying an operating-handle s³. Suitable means are provided for conveniently fastening removably and tightening the generator-cover thus formed of the lid A² and head A³, the means shown comprising uprights t

t, extending from the top of the can *A* at opposite sides of its opening and containing in their upper end portions the recesses *t'* to receive the opposite ends of a cross-head *t²*, the 5 central portion of which is expanded and contains a threaded opening in alignment with the center of the head *A³* to receive a set-screw *t³*, which by bearing against the head tightens it down and thereby also tightens the 10 lid *A²*.

The lower portion of the can *A* affords the carbid-chamber *A⁴*, which I prefer to divide by a central vertical perforated partition *v*, thereby to separate the charge of carbid into 15 two parts the better to prevent it from packing. In the carbid-chamber is a condensation-receiver *C*, formed of an upwardly-converging collar, preferably of sheet metal and affording with the wall of the carbid-chamber 20 an annular trough *l*.

As the gas, heated by the process of its generation, rises from the carbid-chamber by contact with the condenser *C* and walls of the generator the moisture it carries is 25 condensed and is caught in falling on the inclined surface of the trough, down which it trickles to accumulate therein and be emptied in emptying the carbid-holder of sediment. Moreover, by gathering the water of condensation in the trough *l* it is prevented from gaining 30 access to the carbid-chamber and from exerting any influence on the carbid therein, thereby materially facilitating the operation of checking, when desired, the generation of 35 gas by shutting off the supply of water.

B is a gas-holder formed of the telescoping sections or tanks *B'* and *B²*, the former being fixed and containing a body of water, the level of which is indicated at *w* in Fig. 1, and 40 the latter being inverted and seated with its open lower end in this body of water to rise and fall by variation of the volume of gas confined therein. I utilize the water contained in this holder for intermittently supplying therefrom water to the generator, as 45 hereinafter described. For the purpose of guiding the holder-section *B²* in its movements I may provide an upright pipe or rod *k*, extending from the center of the base of the 50 fixed section *B'* and telescoping therewith, a tube *i* depending from the center of the head of the movable section *B²*, beyond which the tube is closed by a cap *x*. A weight *h* may be imposed on the top of the gas-holder *B*, for 55 a purpose hereinafter described, and the top of the movable tank-section should be reinforced from the tube *i* by a brace *g*, shown as a hollow conical body.

A gas-pipe *m³* leads downward in the holder 60 *B* from above the water-line therein and out through one side and is coupled with the pipe *m'*, leading to the generator, to permit the pipe *m'* to be turned by swinging it through a vertical plane, all in a manner and for a 65 purpose hereinafter described.

A water-pipe *m²* leads downward in the

holder *B* from a point below the water-level therein sufficiently deep to clear the surface scum and dirt that accumulates in the upper part of the body of water, and this pipe passes 70 out of the holder through its wall and is coupled with the pipe *m* in the manner of coupling the pipes *m'* and *m³*.

From the portion of the pipe *m³* which projects outside the holder *B*, I extend a pipe *m⁵* 75 upward beyond the water-line in the holder, where it contains a return-bend and extends downward part way throughout the length of its upward-extending section. The pipe *m⁵* thus affords a species of trap, for a purpose 80 hereinafter described.

Outside the holder *B* the pipe *m²* is extended upward to the level of the pipe *m*, with which it is coupled by a species of swivel-joint, (shown at *c*), and the pipe *m'* is similarly coupled with the lower end of the pipe 85 *m⁵*, as shown at *c'*.

In the upper end portion of the pipe *m²* is seated a valve *f*, Fig. 6, to control the inlet of water, as through the lateral inlet shown 90 at *f⁴*, the valve being carried by a stem *f'*, with which engages one end of a lever *f²*, fulcrumed at *y* and carrying at its opposite end a float-ball *f³*, and the downward play of the lever *f²* (at the end of which, owing to the 95 illustrated manner of its connection with the valve-steam *f'*, it opens the valve *f*) is limited by a stop *f⁵*, shown as rising into the path of the lever from the base of the holder *B*.

A collar *e* is adjustably supported on the 100 guide-tube *i* below the plane of the valve-lever *f²* to afford a lifter for a weight *e'*, loosely surrounding the tube above the lever.

The apparatus as thus far described may be complete in itself to operate as follows: 105 With a supply of calcium carbid in the holder *A* and the parts of the gas-holder *B* in the relative positions in which they are illustrated by the full-line representation in Fig. 1, the valve *f* is open to admit water through the 110 pipes *m²* and *m* into the carbid-holder, the water flowing in fine streams through the openings *n'* upon the carbid at opposite sides of the partition *v*. The resulting gas passes off through the pipes *m'*, *m⁵*, and *m³* into the 115 holder *B*, gradually filling the latter and raising the section *B²*, as shown by the dotted lines, and with it the tube *i* and collar *e*, which after the section *B²* has risen to a predetermined height engages with the weight 120 *e'* (by passing through the expanded open section *f²²* of the valve-lever *f²*) and by the continued rise of the gas-holder section induced by the influx of gas into it lifts it from bearing against the valve-lever, the float *f³* 125 on which causes it to rise until its inner end depresses the valve *f* to shut off the water-supply.

The gas may be taken for consumption direct from the holder *B*, and as the supply in 130 the latter becomes less and less the section *B²* falls until the collar *e* passes below the valve-

lever and the weight e' rests upon it and depresses it to the lowest point of its movement, at which it again opens the valve f to supply water to the generator and cause resumption 5 of the gas-generation.

For the more general use of the apparatus, however, a single gas-holder B for storing a sufficient supply of the gas would have to be so large as to render placing the apparatus 10 inconvenient, if not impossible. Accordingly, to enable the holder B to be made of convenient size I supplement it with a second gas-holder D. This holder, containing water, the level of which is indicated at w' , 15 involves the sections D' and D'', like the sections B' and B'' of the holder B, and having the movable section similarly guided by a pipe or rod k' and tube i' , telescoping therewith, equipped with a cap x' , the top of the 20 movable section being reinforced by a brace g' and carrying a weight h' , which, however, is heavier than the weight h . On one side of the section D, eccentrically thereof, is provided a condensing-chamber E, which might 25 be provided on the holder B were the latter used alone. The chamber E is formed on and integral with the fixed section D, the wall of which is the inner wall of the condensing-chamber. Into the lower end of the chamber 30 E the pipe m^3 is extended, and the supply of gas to the consumer is taken from its upper end through a pipe d , and from the lower end of this condenser-chamber a gas-pipe m^4 leads upward in the holder D beyond 35 the water-line therein. Then the gas generated in the manner described first fills the holder B, owing to the imposition thereon of the lesser weight h , and it also fills the condenser-chamber E, and all surplus of the 40 generated gas will enter the holder D through the pipe m^4 , through which it also re-enters the condenser-chamber in being taken off for consumption. Surplus gas will always be generated by the apparatus after shutting off the 45 water-supply through the pipe m^2 to the generator, owing to the impossibility of thereby immediately checking the generation, by reason of the moist condition of the carbid, from which gas will continue to be evolved till the 50 water with which it is more or less saturated becomes exhausted. It is mainly to store and save this surplus that the secondary holder D is provided.

The generator A may be easily and quickly 55 disconnected from the apparatus by loosening the fastening means, after turning the handle s^3 to shut the valves s' and s^2 , and swinging the pipes m m' upward, thereby also raising the head A³ and freeing the lid A² for removal. Then the can A⁷ may be carried 60 away, like an ash-hod, by handles b , provided for the purpose, and dumped of its sediment contents and the water of condensation accumulated in the trough l preparatory to re- 65 charging the chamber A⁴ with a supply of calcium carbid, after which the cover may

be as conveniently readjusted after replacing the can by imposing the lid A² in its place, swinging down upon it the head A³, and applying the fastening means, when upon re-opening the valves s' and s^2 the apparatus is again in condition to resume the generation of gas. 70

The head A³ is a very desirable but not an indispensable feature of my improvement. 75 It may be dispensed with by omitting the central opening from the lid A² and leading the pipes m and m' into the generator immediately through the lid, as represented in Fig. 5, when the lid alone forms the generator-cover. 80

The purpose of the extension m^5 of the pipe m^3 will be understood from the following explanation: When the supply of carbid in the generator and that of gas in the holder 85 B become exhausted, so that the movable section B² falls sufficiently far to open the valve f , water will enter the generator by the pipes m^2 and m' and fill it and rise in the pipe m^5 to the water-level in the gas-holder, so that 90 when the generator is emptied, recharged with carbid, and replaced and the valves s' s^2 after having been closed are again opened the amount of water standing in the pipe m^5 may flow into the generator and is not in excessive amount for attacking the calcium carbid. If, however, the rising pipe m^5 were not provided, under the conditions of exhaustion named the generator would not only be filled with water, but the condensing-chamber 95 E would also be filled therewith through the gas-pipes m' and m^3 , and the amount therein flowing back into the generator would be greatly excessive. Of course 100 this riser may be employed whether one or more gas-holders be contained in the system. 105

What I claim as new, and desire to secure by Letters Patent, is—

1. In a gas-generating apparatus, the combination with a gas-holder, of a carbid-holder 110 or generator proper provided with a detachable cover, a gas and water pipe connection between said gas-holder and generator having fixed connection with and leading through the cover, and a flexible joint in said connection affording a hinge for the cover whereby the latter may be detached from the generator and supported by the pipe connection, substantially as and for the purposes set forth. 115

2. In a gas-generating apparatus, the combination with a gas-holder of a carbid-holder 120 or generator proper, and gas and water pipes containing shut-off valves on a common stem provided with a handle, said pipes leading respectively to and from said gas-holder and 125 through the cover of the generator and having flexibly-jointed sections adapting them to be swung to remove and replace the cover, substantially as described.

3. In a gas-generating apparatus, the combination with a gas-holder of a carbid-holder 130 or generator proper having a cover compris-

ing an annular lid and a hollow chambered head seating therein, fastening means for the cover, and gas and water pipes leading respectively to and from said gas-holder into 5 the chambers in said head and having flexibly-jointed sections adapting them to be swung to lift and lower said head, and a nozzle extending from a chamber in said head to enter said carbide-holder, substantially as described.

4. In a gas-generating apparatus, the combination with a gas-holder, of a carbide-holder or generator proper, a gas-pipe leading from said holder and connected with the generator, a water-trap extension connected with the gas-pipe and extending above the water-level in the said holder, and a water-supply pipe for the generator connected with said extension, substantially as described.

20 5. In a gas-generating apparatus, the combination with a gas-holder of a carbide-holder or generator proper, and gas and water pipes leading respectively to and from said gas-holder and through the cover of the generator and having flexibly-jointed sections adapting them to be swung to remove and replace the cover and a rising extension of the water-pipe without the gas-holder reaching above the water-level therein and having a 25 return-bend with which the flexible junction of the water-pipe section is made, substantially as and for the purpose set forth.

30 6. In a gas-generating apparatus, the combination with a gas-holder of a portable carbide-holder or generator proper supported extraneously of said gas-holder and provided with a cover comprising an annular lid and a hollow head seating therein and containing water and gas chambers, a nozzle extending 35 from the water-chamber in said head to enter the carbide-holder, gas and water pipes connecting said gas-holder respectively with said gas and water chambers and having flexibly-jointed sections adapting them to be swung 40 to lift and lower said head, and shut-off valves in said pipes, substantially as described.

45 7. In a gas-generating apparatus, the combination of a carbide-holder or generator proper and a water-containing gas-holder formed of the stationary and movable telescoping sections, and having a pipe connection with said generator for supplying water thereto, a valve in said pipe connection, an operating-lever 50 therefor carrying a float, a weight loosely supported on said lever and a stop carried by the movable section and adapted in the movement of the latter to coöperate with the weight and thereby permit of the controlling of the 55 valve by the lever, substantially as and for the purpose described.

60 8. In a gas-generating apparatus, the combination of a carbide-holder or generator proper and a water-containing gas-holder intercommunicating through a gas-pipe, a water-pipe 65 connecting said generator with said gas-holder

and containing a valve controlling the supply of water to the generator for promoting the generation of gas therein, a lever connected with said valve and carrying a float, a telescoping guide extending between the fixed and movable sections of said gas-holder, a weight on said guide above said lever and a lifter on the movable portion of said guide below the weight, substantially as and for the 75 purpose set forth.

9. In a gas-generating apparatus, the combination of a carbide-holder or generator proper and a water-containing gas-holder intercommunicating through a gas-pipe, a water-pipe 80 connecting said generator with said gas-holder and containing a valve controlling the supply of water to the generator for promoting the generation of gas therein, a lever connected with said valve and carrying a float, a telescoping guide extending between the fixed and movable sections of said gas-holder, a weight on said guide above said lever, a lifter on the movable portion of said guide below the weight, and a stop below the lever for 85 limiting its downward throw, substantially as and for the purpose set forth.

10. In a gas-generating apparatus, the combination with a carbide-holder or generator proper, of two gas-holders each comprising a 90 fixed section and a movable section, the movable sections being differentially weighted, said holders having gas communication with each other and with said generator and the lesser-weighted gas-holder having a water-pipe connection with said generator controlled by a valve actuated by the rise and fall of the movable gas-holder section to regulate the supply of water to the generator for promoting the generation of gas therein, and an outlet in the heavier-weighted holder for leading therefrom the gas to the point of consumption, substantially as and for the purpose set forth.

11. In a gas-generating apparatus, the combination with a carbide-holder or generator proper, of two gas-holders each comprising a fixed section and a movable section, the movable sections being differentially weighted, a condenser on the holder having the heavier-weighted section provided with an outlet-pipe 115 d and communicating through a pipe m^4 with the interior of said holder, a gas-pipe connection between the gas-holder having the lesser-weighted section, the said condenser and said generator and a water-pipe connecting said last-named gas-holder with the generator and containing a valve actuated by the rise and fall of the movable section of said gas-holder 120 to regulate the supply of water to the generator for promoting the generation of gas therein, substantially as described.

12. A gas-generating apparatus comprising, in combination, a generator A, a gas-holder D provided with a condenser E having an outlet d and a pipe connection m^4 with the interior of the holder, a weight h' on the movable

section of said holder, a gas-holder B carrying a weight h on its movable section of lesser gravity than that on the holder D, a gas-pipe m^3 connecting the holder B with the condenser E, a valve-controlled water-pipe m^2 leading from said holder B, and valve-controlled pipe-sections m and m' flexibly jointed, respectively, to the pipes m^2 and m^3 and leading

into said generator through its cover, the whole being constructed and arranged to operate substantially as described.
